(57) **CLAIM**

The ornamental design for a locker organizer, as shown and described.

DESCRIPTION

FIG. 1 is an upper perspective view of the locker organizer showing my new design.

FIG. 2 is a front view thereof;

FIG. 3 is a back view thereof;

FIG. 4 is a side view thereof;

FIG. 5 is an opposite side view thereof;

FIG. 6 is a top view thereof;

FIG. 7 is a bottom view thereof; and,

FIG. 8 is an upper perspective view showing the locker organizer in an expanded state.

The broken lines in FIGS. 1, 4 and 5 illustrate portions of the locker organizer that form no part of the claimed design.
